UNITED STATES PATENT OFFICE.

PAUL SCHEIDECKER AND FRANK SCHEIDECKER, OF PARIS, FRANCE, ASSIGNEES TO
CHENEY BROTHERS, OF SOUTH MANCHESTER, CONNECTICUT, A CORPORATION OF
CONNECTICUT.

DESIGN FOR TEXTILE FABRIC.

41,912.

Specification for Design.

Patented Nov. 7, 1911.

Application filed August 3, 1911. Serial No. 642,130 $\frac{1}{2}$. Term of patent 3 $\frac{1}{2}$ years.

To all whom it may concern:

Be it known that we, PAUL SCHEIDECKER and FRANK SCHEIDECKER, citizens of France, residing at Paris, France, have invented a new, original, and ornamental Design for Textile Fabrics, of which the following is a specification, reference being had to the accompanying drawing, forming a part thereof.

The single figure of the drawing is a plan

view of a portion of a textile fabric illustrating our new design.

We claim:

The ornamental design for a textile fabric, as shown.

PAUL SCHEIDECKER.
FRANK SCHEIDECKER.
